DESIGN FOR AN UPHOLSTERY FABRIC

Walter Mitschke, North Plainfield, N. J.

Application March 10, 1936, Serial No. 61,548

Term of patent 3½ years

To all whom it may concern:

Be it known that I, Walter Mitschke, a citizen of the United States, residing at 472 Watchung Avenue, North Plainfield, county of Union, State of New Jersey, have invented a new, original, and ornamental Design for an Upholstery Fabric, of which the following is a specification, reference being had to the accompanying drawing, forming a part thereof.

The figure is a plan view of an upholstery fabric showing my design.

I claim:

The ornamental design for an upholstery fabric as shown.

In testimony whereof I have signed this specification.

WALTER MITSCHKE.
